MECHANICAL LOADER FOR RIVETING MACHINES

Donald C. Draper, Jackson, Mich., assignor to
Tomkins-Johnson Company, Jackson, Mich., a
corporation of Michigan

Application October 24, 1938, Serial No. 236,657

15 Claims. (Cl. 78—49)

This invention relates to riveting machines and the like and more particularly to such a machine having a movable anvil.

In the application Serial No. 192,946, filed by Loyd A. Ward et al., February 28, 1938, was disclosed one form of mechanism for depositing a rivet or other upsettable member on a movable anvil when the anvil is disposed out of cooperating relation with the rivet set. The present invention comprises another form of mechanism for feeding rivets or other upsettable members to a movable anvil while it is out of cooperating relation with the rivet set.

An object of the present invention is to provide a riveting machine or the like having an anvil which is laterally movable with respect to the set and mechanism for projecting a rivet on the anvil while it is out of cooperating relation with the set.

Another object of the invention is to provide a riveting machine or the like having a movable anvil laterally movable with respect to the set, rivet clamping jaws spaced laterally from the set and means for ejecting a rivet from between said jaws onto the anvil while it is out of cooperating relation with the set.

A further object of the invention is to provide a riveting machine or the like having a laterally movable anvil with the mechanism, the operation of which is timed by the movement of the anvil for depositing a rivet on the anvil and also for selecting a rivet from a source to be deposited on the anvil.

These and other objects will be apparent from the following specification when taken with the accompanying drawings, in which:

Fig. 1 is a side elevation partially broken away through the machine comprising my invention,

Fig. 2 is a section on the line II—II of Fig. 1, and

Fig. 3 is a section on the line III—III of Fig. 2.

Referring particularly to the drawings, the reference character 1 indicates a frame on which is mounted a laterally slidable anvil 2. Arranged above the anvil 2 in its extreme forward position, as shown in Fig. 1, is a set 3 mounted in a ram 4 arranged for vertical reciprocatory movement in a conventional manner.

The anvil 2 is secured in a base 5 by a screw 6, the base 5 being provided at its bottom with flanges 7, shown particularly in Fig. 2, for coacting with ways 8. The base 5 is connected to a piston rod 9 reciprocated by a piston (not shown) in a fluid cylinder 10. The specific connection between the piston rod 9 and the base 5 comprises an exten-

sion 11 from the piston rod 9 projecting through a restricted bore 12 in one end of the base 5 into an enlarged bore 13 within the base 5. The extension 11 has disposed thereabout a helical spring 14 bearing at one end against a head 15 on the extension 11 and at the other end against a shoulder 16 within the base 15. Mounted in the frame 1 is a stop rod 20 arranged to abut against the rear end of the base 5 as it moves rearwardly or to the right, as disclosed in Fig. 1. Thus, as the piston rod 9 moves rearwardly the base 5, carrying with it the anvil 2, is moved rearwardly until the base 5 abuts against the stop 20. The piston rod 9 is arranged to move slightly further to the rear so that the base 5 is resiliently urged against the stop 20 by the spring 14. The use of the stop 20 assures that the anvil 2 will always be at a predetermined position at the end of its rearward movement.

Disposed directly above the anvil 2 in its rearward position are rivet clamping jaws 21 mounted on cantilever leaf springs 22. The jaws 21 may be of the character disclosed in the copending application, Ser. No. 101,210, of Loyd A. Ward. Communicating with the jaws 21 is a chute 23 having associated therewith a rivet selector 24. The selector 24 is like that disclosed in the aforesaid copending application of Ward et al., Ser. No. 192,946, and operates each time it is reciprocated to select one rivet from the chute 23 above it and permit it to slide downwardly to between the jaws 21.

Arranged directly above the jaws 21 is a guide 25 having disposed therein a reciprocable plunger 26. The guide 25 has in the side thereof a slot 27 through which projects a pin 28 extending through a slot 29 in an arm 30 of a bell crank lever 31. The bell crank lever 31 is pivoted about a pin 32 and has a depending arm 33 arranged beside the piston rod 9. Extending laterally from the arm 33 is a rod 34 having connected to the end thereof a helical spring 35, the free end of which is connected to a part of the frame 1 by a screw 36. The action of the spring 35 is to resiliently urge the bell crank lever 31 in a clockwise direction, as viewed in Fig. 1.

The piston rod 9 has adjustably connected thereto a collar 40, which is in the path of movement of the arm 33. Thus, as the piston rod 9 moves rearwardly, the collar 40 engages the arm 33 to rock the arm 30 downwardly and with it the plunger 26. As the plunger 26 is disposed directly above the jaws 21, and the rivet or upsettable member held by the jaws 21, downward movement of the arm 30 forces the rivet or up-

settable member from the jaws 21 onto the anvil 2. Preferably, the anvil 2 is provided with a recess 41, into which the tail piece of the particular form of upsettable member disclosed is projected by the plunger 26.

The bell crank lever 32 has projecting upwardly therefrom a cantilever leaf spring 43, which is connected to a rod 44 projecting from the rivet selector 24. Thus, as the bell crank lever 31 is rocked about its pivot 32, the selector 24 is reciprocated. The selector 24 is arranged so that as the bell crank lever 31 pivots in a clockwise direction, the selector 24 operates to select a rivet from the chute 23 above the selector 24 and permit it to drop to the chute below the selector 24 and thus into the jaws 21. It will be understood that as the rivet from the selector 24 is dropping into the jaws 21, the plunger 26 is moving upwardly from between the jaws 21. The leaf spring 43 is connected to the rod 44 by nuts 45 threaded on the rod 44 so that the movement of the selector 24 may be properly timed with respect to the upward movement of the plunger 26.

In operation of the machine according to the present invention, when the base 5 moves rearwardly and engages with the stop 20, to position the anvil 2 with respect to the jaws 21, the collar 40 engages with the depending arm 33 to move the plunger 26 downwardly to force a rivet from between the jaws 21 into the recess 41 in the anvil 2. Then, as the piston rod 9 moves forwardly to move the anvil 2 forwardly, the release of pressure of the collar 40 against the arm 33 permits the spring 35 to operate to lift the arm 30 and thus the plunger 26. At the same time the selector 24 is moved, through the cantilever leaf spring 43, to release a rivet and drop it into position between the jaws 21. When the anvil 2 reaches its forward position having the rivet upstanding therein, work 46 is disposed over the rivet and the set 3 operated to upset the rivet over the work.

While the invention has been described as being particularly usable for a rivet having a depending shank, it will be understood that it may be used for other types of rivets or upsettable members or their equivalents. Also, the invention is not limited to the specific form of anvil shown. In the claims it is to be understood that the rivet is intended to mean upsettable members in general and their equivalents.

Having thus described my invention, what I desire to secure by Letters Patent and claim is:

1. A machine of the character described, comprising a set, means to operate said set, a movable anvil, means to move said anvil into and out of cooperating relation with said set, rivet holding jaws spaced to one side of said set, means to feed a rivet into said jaws, and means to transfer a rivet from said jaws to said anvil when said anvil is out of cooperating relation with said set.

2. A machine of the character described, comprising a set, means to operate said set, a movable anvil, means to move said anvil into and out of cooperating relation with said set, rivet holding jaws spaced to one side of said set, means to feed a rivet into said jaws, and means operable by said anvil moving means to transfer a rivet from said jaws to said anvil when said anvil is out of cooperating relation with said set.

3. A machine of the character described, comprising a set, means to operate said set, a movable anvil, means to move said anvil into and out of cooperating relation with said set, rivet

holding jaws spaced to one side of said set, a reciprocating plunger for forcing a rivet out of said jaws onto said anvil, and an operating connection between said plunger and said anvil moving means.

4. A machine of the character described, comprising a set, means to operate said set, a movable anvil, means to move said anvil into and out of cooperating relation with said set, rivet holding jaws spaced to one side of said set, means to feed a rivet into said jaws, means to transfer a rivet from said jaws to said anvil when said anvil is out of cooperating relation with said set, a lever for actuating said rivet transferring means, and an operating connection between said lever and said anvil moving means for moving said lever to actuate said rivet transferring means.

5. A machine of the character described, comprising a set, means to operate said set, a movable anvil, means to move said anvil into and out of cooperating relation with said set, rivet holding jaws spaced to one side of said set, means to feed a rivet into said jaws, means to transfer a rivet from said jaws to said anvil when said anvil is out of cooperating relation with said set, and a single rigid structure operable in one position to actuate said rivet feeding means and in another position to actuate said rivet transferring means.

6. A machine of the character described, comprising a set, means to operate said set, a movable anvil, means to move said anvil into and out of cooperating relation with said set, rivet holding jaws spaced to one side of said set, a plunger for transferring a rivet from said jaws to said anvil when said anvil is out of cooperating relation with said set, a bell crank lever for actuating said plunger, and an operating connection between said anvil moving means and said bell crank lever for actuating the latter when said anvil is moved out of cooperating relation with said set.

7. A machine of the character described, comprising a set, means to operate said set, a movable anvil, means to move said anvil into and out of cooperating relation with said set, rivet holding jaws spaced to one side of said set, a plunger for transferring a rivet from said jaws to said anvil when said anvil is out of cooperating relation with said set, a bell crank lever for actuating said plunger, an operating connection between said anvil moving means and said bell crank lever for actuating the latter when said anvil is moved out of cooperating relation with said set, and an operating connection between said bell crank lever and said rivet feeding means for actuating said feeding means to feed a rivet into said jaws in one position of said bell crank lever.

8. A machine of the character described, comprising a set, means to operate said set, a movable anvil, means to move said anvil into and out of cooperating relation with said set, rivet holding jaws spaced to one side of said set, means to feed a rivet into said jaws, means to transfer a rivet from said jaws to said anvil when said anvil is out of cooperating relation with said set, a lever for actuating said rivet transferring means, and operative connections between said lever, said rivet feeding means and said anvil moving means for actuating said rivet feeding means in timed relation to the actuation of said rivet transferring means.

9. In a riveting machine, a rivet source, jaws

for holding a selected rivet, means to select a rivet from said source and to transfer it to said jaws, a rivet support movable relatively to said jaws, means for effecting relative movement between said jaws and said support, means for transferring a rivet from said jaws to said support when said support and jaws are in a predetermined relation, and an operative connection comprising a single rigid member between said rivet transferring means and said relative movement effecting means for causing said relative movement effecting means to actuate said rivet transferring means to transfer rivets from said rivet support.

10. In a riveting machine, a rivet source, jaws for holding a rivet, a rivet selector for selecting a rivet from said source and feeding it to said jaws, means for ejecting a rivet from said jaws, a cantilevered leaf spring projecting from said ejecting means, and an operative connection between said leaf spring and selector for moving said selector in timed relation to the movement of said ejecting means.

11. A machine of the character described, comprising a set, means to operate said set, a movable anvil, means to move said anvil into and out of cooperating relation with said set, rivet holding jaws spaced to one side of said set, said anvil when out of cooperating relation with said set being in alignment with said jaws, means for transferring a rivet from said jaws onto said anvil, a lever for actuating said rivet transferring means, and an abutment movable with said anvil moving means for engaging with said lever for actuating the same to transfer a rivet onto said anvil when said anvil is in alignment with said jaws.

12. A machine of the character described, comprising a set, means to operate said set, a movable anvil, means to move said anvil into and out of cooperating relation with said set, rivet holding jaws spaced to one side of said set, means to transfer a rivet from said jaws onto said anvil when said anvil is in alignment with said jaws, a rivet source, a selector for selecting a rivet from said source and feeding it to said jaws, an operative connection between said rivet transferring means and said selector, and an abutment movable with said anvil moving means to actuate said rivet transferring means and said selector in timed relation.

13. A machine of the character described, comprising a set, means to operate said set, a movable anvil, means to move said anvil into and out of cooperating relation with said set, rivet holding jaws spaced to one side of said set, a bell crank lever having one arm depending into the path of movement of said anvil moving means, an abutment on said anvil moving means for cooperating with said depending arm to actuate said bell crank lever, said bell crank lever having another arm projecting laterally, a plunger for transferring a rivet from said jaws onto said anvil, and an operative connection between said laterally extending arm and said plunger.

14. A machine of the character described, comprising a set, means to operate said set, a movable anvil, means to move said anvil into and out of cooperating relation with said set, rivet holding jaws spaced to one side of said set, a rivet source, a rivet selector for selecting a rivet from said source and feeding it to said jaws, a bell crank lever having one arm depending into the path of movement of said anvil moving means, an abutment on said anvil moving means for cooperating with said depending arm to actuate said bell crank lever, said bell crank lever having another arm projecting laterally, a plunger for transferring a rivet from said jaws onto said anvil, an operative connection between said laterally extending arm and said plunger, a leaf spring projecting upwardly from said bell crank lever, and an operative connection between said selector and said leaf spring whereby movement of said anvil, said rivet transferring means and said selector are effected in timed relation.

15. A machine of the character described, comprising a set, means to operate said set, a movable anvil, means to move said anvil into and out of cooperating relation with said set, rivet holding jaws spaced to one side of said set, said anvil when out of cooperating relation with said set being in alignment with said jaws, means for transferring a rivet from said jaws onto said anvil, means for actuating said rivet transferring means, and an operative connection between said actuating means and said anvil moving means for actuating said rivet transferring means to transfer a rivet onto said anvil when said anvil is in alignment with said jaws.

DONALD C. DRAPER.
